DESIGN FOR A FLEXIBLE POCKET RECEPTACLE

Helen L. Richards, Springfield, Mass., assignor
to Buxton, Incorporated, Springfield, Mass., a
corporation of Massachusetts

Application April 6, 1933. Serial No. 47,710

Term of patent 14 years

To all whom it may concern:

Be it known that I, HELEN L. RICHARDS, a citizen of the United States, residing at Springfield, in the county of Hampden and State of Massachusetts, have invented a new, original, and ornamental Design for Flexible Pocket Receptacles, of which the following is a specification, reference being had to the accompanying drawing, forming, forming part thereof.

Fig. 1 is a top plan view of a bill fold in which my new design is embodied; and

Fig. 2 is a front elevational view of the bill fold showing the design.

The design appears wholly on the front side of the bill fold shown in Fig. 2, the reverse side

being plain. The design is essentially characterized by the sets of upwardly curving and diverging lines, there being one such set on each side of the vertical center line of the bill fold and each set comprising a plurality of lines which start from a common point near the lower edge of the bill fold and curve upwardly in diverging relation, and in diverging relation with the lines of the other set, and terminate at longitudinally spaced points near the upper edge of the bill fold.

I claim:

The ornamental design for a flexible pocket receptacle substantially as shown and described.

HELEN L. RICHARDS.
